UNITED STATES PATENT OFFICE.

THERIDES V. BARNARD, OF SCHALLER, IOWA, ASSIGNOR OF ONE-HALF TO MARTIN SHELEY, OF SCHALLER, IOWA.

PULVERIZER AND LEVELER.

No. 909,051.

Specification of Letters Patent.

Patented Jan. 5, 1909.

Application filed February 6, 1908. Serial No. 414,616.

To all whom it may concern:

Be it known that I, THERIDES V. BARNARD, a citizen of the United States, residing at Schaller, in the county of Sac and State of Iowa, have invented certain new and useful Improvements in Pulverizers and Levelers; and I do hereby declare the following to be a full, clear, and exact description of the invention, such as will enable others skilled in the art to which it appertains to make and use the same.

The present invention has reference to combined pulverizers and levelers, and it aims, generally, to provide an exceedingly simple, durable and efficient apparatus of that nature including a plurality of sets of different ground-treating implements, which are capable of adjustment and operation independently of each other.

More especially, the invention resides in the provision of an apparatus of the above specified type in which the ground-treating implements are carried by rock-bars arranged transversely of the frame of the apparatus, in sets of two or more, as preferred, the several bars of each set having a pivotal connection with a floating rod which likewise has a pivotal connection with an operating lever fulcrumed at its lower end upon a pin set laterally into the adjacent longitudinal sill, whereby movement of any one of the levers will effect a partial rotation of the several rock-bars connected therewith, so as to adjust the inclination of the ground-treating implements with which said bars are provided.

The invention further resides in the attachment to each of the several sills of a longitudinal series of depending plates, each of which is provided with an integral bearing sleeve projecting laterally therefrom, the plates upon one sill being so arranged with respect to those of the other sills that the bearing sleeves of corresponding plates align with each other, thus permitting the passage of the rock-bars therethrough.

The invention still further resides in the provision between the central pair of sills of an elevated track upon which a wheeled carriage is adapted to travel, the occupant of the seat of the carriage shifting the latter at will, to bring himself into a convenient position for operating any one of the above-mentioned levers.

The invention still further resides in the particular construction and disposition of the traveling seat with relation to an apparatus of the specified type comprising two or more connected sections.

The preferred embodiment of the invention is illustrated in the accompanying drawings, in which corresponding parts or features are designated by the same reference numerals in the several views.

Of the said drawings, Figure 1 is a plan view of the improved pulverizer and leveler in its simplest form. Fig. 2 is a side elevation thereof. Fig. 3 is a plan view of a duplex pulverizer and leveler embodying the invention.

Referring more particularly to the drawings, the main frame of the apparatus is shown as comprising a plurality of parallel longitudinal sills 5 arranged in spaced relation to each other, each sill being secured thereto a series of metal plates 6 whose flanged upper ends rest upon the upper faces of the sills. The body portion of each plate, which depends below the under face of the corresponding sill is provided with a tubular bearing sleeve 7 which is formed integral therewith and is disposed at right angles thereto and to the sill. The plates and their sleeves on each sill are positioned directly opposite those on the other sills, so that the sleeves on each row of plates (the rows being formed by the above described arrangement of the plates) form supporting bearings for a metal rock-bar which is disposed transversely of the frame, as shown. The several rock-bars are held against endwise movement by means of split-pins 9 which extend through openings formed in the sleeves and through registering transverse slots formed in the rock-bars.

The front pair of rock-bars 8 and 8' carry ground treating implements 10 and 10' in the form of rearwardly and downwardly inclined blades, as shown in Fig. 2, the laterally bent upper ends of the blades being secured to the under face of the rock-bars, (which are preferably formed of angle-iron), by means of bolts or rivets. The central pair of rock-bars 11 and 11' carry similarly-inclined blades 12 and 12' which however, are angular in shape, the lower portion of each blade 12, moreover, being bent to one side of the upper portion thereof, while that of each blade 12' is bent

to the other side, as shown in Fig. 1. The three rear rock-bars 13, 13' and 13'', carry respectively, leveling plates 14 and 14', and rake teeth 15, the blades 12 and 12' and plates 14 and 14' being bolted to the corresponding rock-bars, while the teeth 15 are secured to the rock-bar 13'' by means of nuts which are threaded upon the reduced upper ends of the teeth and are adapted to be tightened against the adjacent face of said rock-bar. It will thus be seen that the several rock-bars are arranged in three separate sets, the front pair 8 and 8' forming the first set, the central pair 11 and 11', the second set, and the three remaining bars 13, 13' and 13'', the third set. Each set is intended to be actuated separately, and the position of the ground-treating implements carried thereby adjusted independently of those of the other sets, to suit the implements of each set to the particular character of the ground operated upon, or for various other reasons. To this end, the right-hand member of the central pair of sills has pivoted thereto the lower ends of three levers 16, 16' and 16'', which control the movement, respectively, of the front, central, and rear sets of bars. Above their first-mentioned pivot points, the levers have pivotal connections with floating rods or links 17, 17' and 17'', adjacent the rear ends of the latter, said rods being arranged parallel with the above-mentioned sill and in alinement with each other. These rods are pivotally connected with the upper ends of straps 18 whose lower ends are rigidly secured to the adjacent rock-bars; thus, the rod 17 is connected with the bars 8 and 8', the rod 17' with the bars 11 and 11' and the rod 17'' with the bars 13, 13' and 13''. Each lever carries a spring pressed dog 19 adapted in its normal position, for engagement in one of the openings formed in a vertical rack 20, secured to the adjacent floating rod, by reason of which construction it will be apparent that the movement of any one of the operating levers in one direction or the other, will effect a rocking movement simultaneously of the bars with which it is connected through the medium of the corresponding floating rod, with a resultant variation in the position of the ground-treating implements carried by said bars, the rocking movement of the bars being limited by the length of the slots formed therein and above referred to.

The members of the central pair of sills are connected with the adjacent end sills by means of braces 21, while to said central sills are further secured the outer ends of braces 22 whose inner ends support a platform 23 disposed parallel with and intermediate said sills, as shown in Fig. 1. To the upper face of said platform is attached a longitudinal track 24 upon which travels a carriage 25 comprising a pedestal and a seat mounted upon the upper end thereof, the base of the

pedestal having secured thereto pair of rollers or wheels 26 which run along the track rails.

The front end of each sill 5 has secured thereto one end of a short chain 27 whose other end is attached to a ring 28 to which the draft animals are hitched.

The duplex machine shown in Fig. 3 comprises a pair of sections A and B both of which are identical in the main with the single section shown in Figs. 1 and 2, the rods being located to the right of the center of the right hand section B and to the left of the center of the left hand section A. These sections are joined together by means of pairs of diagonally-disposed linked braces 29 and 30, the front ends of each pair of braces being attached to the hitching ring 28' of one section, while their rear ends are attached to the front and rear ends of the adjacent sill 5 of the other section. The mutually-adjacent ends of the front and rear rock-bars 8 and 13'' of the two sections are likewise connected together by links 31 and 32, each of which carries a pair of eye-bolts 33 set into the ends of said rock-bars. In this form of the invention, the carriage shown in Figs. 1 and 2 is replaced by a double carriage 25' which has a length sufficient to extend from the platform 23 of one section to the platform 23' of the other section, said carriage being provided at each end with a depending pedestal whose rollers travel along the rails of the tracks 24 and 24'. It is, therefore, possible for the occupant of the seat to shift the carriage in either direction upon the track, into position for operating any one of the levers. It will also be obvious that the occupant or occupants of the single or double carriages may shift the same into position conveniently close to the particular lever or levers to be operated.

What is claimed is:

1. In a machine of the class described, the combination, with a frame, of a plurality of sets of transverse rock-bars carried by the frame; ground-treating implements secured to each rock-bar; separate devices for actuating each set of rock-bars; a platform mounted upon the frame; and a traveling carriage movable upon said platform into position adjacent any one of said actuating devices, to permit the same to be operated.

2. In a machine of the class described, the combination with a frame, comprising a series of longitudinal sills, of a plurality of sets of transversely-disposed rock-bars carried by said sills; ground-treating implements secured to each rock-bar; a separate lever for actuating each set of rock-bars; a platform mounted upon said sills; and a traveling carriage movable upon said platform into position adjacent any one of said levers, to permit the same to be operated.

3. In a machine of the class described, the

combination, with a frame, comprising a series of longitudinal sills, of a plurality of sets of transversely-disposed rock-bars carried by said sills; ground-treating implements secured to each rock-bar; a separate lever for actuating each set of rock-bars; a platform mounted upon said sills; a track secured to said platform; and a traveling carriage movable in either direction upon said track into position adjacent any one of said levers, to permit the same to be operated, said carriage including a base member provided with wheels engaging the track.

4. In a machine of the class described, the combination of a plurality of connected sections, each including a frame, a plurality of sets of transverse rock-bars carried thereby,

ground-treating implements secured to each rock-bar; and separate devices for actuating each set of rock-bars; a longitudinal platform secured to each frame; a track secured to each platform; and a transversely-disposed carriage extending across said frames and provided with wheeled supporting members engaging the several tracks, whereby the carriage may be moved in either direction upon said tracks, to permit the operation of any one of said actuating devices.

In testimony whereof, I affix my signature, in presence of two witnesses.

THERIDES V. BARNARD.
